US0D1008402S

(12) **United States Design Patent** (10) **Patent No.:** **US D1,008,402 S**
(45) **Date of Patent:** **** Dec. 19, 2023**

(54) **LASER SIGHT**

(71) Applicant: **Shenzhen Xinyue Han Technology Co., Ltd.**, Shenzhen (CN)

(72) Inventors: **Xiaobo Wan**, Xiangxi Tujia and Miao Autonomous Prefec (CN); **Jingqi Li**, Durham, NC (US)

(73) Assignee: **Shenzhen Xinyue Han Technology Co., Ltd.**, Shenzhen (CN)

(**) Term: **15 Years**

(21) Appl. No.: **29/829,599**

(22) Filed: **Mar. 7, 2022**

(30) **Foreign Application Priority Data**

Feb. 24, 2022 (CN) 202230089965.8

(51) **LOC (14) Cl.** **22-01**

(52) **U.S. Cl.**

USPC **D22/109**; D26/60

(58) **Field of Classification Search**

USPC D22/108, 109, 110; D26/60; D10/70

CPC F41G 1/02; F41G 1/06; F41G 1/16; F41G

(57) **CLAIM**

The ornamental design for a laser sight, as shown and described.

DESCRIPTION

FIG. 1 is a perspective view of a laser sight, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken line in the drawings depicts unclaimed portions of the laser sight only and forms no part of the claimed design.

1 Claim, 8 Drawing Sheets
